Brew Movers, LLC, Canadian Design Application No. 200543, Examination Report, Apr. 27, 2022.

Primary Examiner — Cynthia Ramirez

(74) *Attorney, Agent, or Firm* — Moore & Van Allen PLLC; R. W. McCord Rayburn

(57) **CLAIM**

The ornamental design for a pallet cover, as shown and described.

DESCRIPTION

FIG. 1 is a front perspective view of a pallet cover system showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a top plan view thereof in a flat configuration; and,

FIG. 9 is a bottom plan view thereof in the flat configuration. The broken lines in the figures show portions of the pallet cover system, which form no part of the claimed design.

1 Claim, 7 Drawing Sheets
